MACHINE FOR TREATING FLAX AND THE
LIKE

Karl Wessel, deceased, late of Los Angeles, Calif.,
by Leland O. Walker, administrator, Los Angeles, Calif., assignor of one-fourth to Charles S. Kirkpatrick, Bloomington, Ill., and three-fourths to American Fiber Corporation, a corporation of Nevada

Application August 5, 1939, Serial No. 288,644

9 Claims. (CL. 19—5)

This invention relates to the machines for the treatment of fiber bearing straw or stocks, and while especially designed for the treatment of flax and hemp straw as it comes from the field, 5 is, nevertheless, capable of a wider range of uses.

The machine involves elements adapting it to take the straw as it comes from the field, perform the various operations necessary to convert 10 the fiber into clear fiber capable of being used for spinning and various analogous purposes according to the grade of flax.

This flax fiber, usually designated as tow, is the main product of the machine. By the various operations performed in accomplishing the 15 above major result, the woody portion or shives will be removed from the fiber and the seed, if present, will also be delivered from the machine. Generally stated the invention consists of the 20 novel devices, combination of devices and arrangement of parts hereinafter described and defined in the claims.

The machine, in what is at present believed to be its preferred form, is illustrated in the accompanying drawings wherein like characters indicate like parts throughout the several views.

Because of the very great length of the complete machine it has been necessary to make the 30 patent drawings thereof in sections. These sections are arbitrary and made of such length that each section will properly go on a single sheet of patent drawings.

Referring to the drawings:

Figs. 1, 1a and 1b are side elevations with certain parts conventionally or diagrammatically shown;

Fig. 1 is a side elevation of the first section or part of the machine;

Fig. 1a is a side elevation of the second section or part of the machine; and

Fig. 1b is a side elevation of the third or last section of the machine;

Fig. 2 is a plan view of the parts shown in Fig. 1 with the feeding mechanism of the machine omitted;

Fig. 2a is a plan view of the parts shown in Fig. 1a;

Fig. 2b is a plan view of the parts shown in Fig. 1b with the single breaking drum and certain other cooperating devices not shown;

Figs. 3, 3a and 3b are vertical longitudinal sections taken through the machine;

Fig. 3 is a section through the parts shown in Figs. 1 and 2;

Fig. 3a is a section taken through the parts shown in Figs. 1a and 2a; and

Fig. 3b is a section taken through the parts shown in Figs. 1b and 2b.

Here it may be stated that in Figs. 2a and 2b certain parts such as upper casings and fans are omitted to better show the drum and roller structures.

The frame work for the complete machine is a preferably continuous rigidly connected or integral structure, but for the purpose of this case the first frame section is here indicated by the numeral 10, the frame for the second section is indicated by 10a and the frame section for the third is indicated by 10b.

The flax as it comes from the field or otherwise prepared may be delivered to the machine proper in various different sizes, but for that purpose is shown a power driven elevated belt 11 which delivers the straw to a power driven toothed picker drum 12 in the direction indicated by the arrow on Fig. 3, and works over a concave hopper 13 that delivers the straw between cooperating upper and lower power driven rollers 14.

From the rollers 14 the straw will be driven on to an endless tooth equipped spreader belt 15 that runs over power driven sprockets 16 journaled on the frame 10a. Belt 15 is driven in the direction of the arrow marked in Figs. 1 and 3.

The straw, indicated by y in Figs. 1 and 3 in the arrangement shown, is carried under rotary gravity held rollers 17 which latter feature, however, constitutes no important part of the invention.

The belt 15 delivers the thin sheet of spread out straw y between a multiplicity of corrugated lower rollers 18 and corrugated upper rollers 19, which rollers are driven in the direction of the arrow marked on Fig. 3 and progressively feed the stock in a direction from left toward the right in respect to Figs. 1 and 3.

In practice the upper rollers 19 will preferably be downwardly spring pressed by means such as that illustrated in Fig. 14 of the Karl Wessel prior Patent No. 1,592,317. The rollers 18—19 have corrugations that, in a direction from left toward the right, are progressively finer and finer, so that they will progressively shorten the kinks in the straw and reduce the woody portions to finer and finer form. For example, the first rollers 18—19 may have sixteen corrugations and the last roller may have as much as fifty-six corrugations.

The corrugated rollers 18—19 operate as decor-

ticating elements which break up the woody portions of the straw and initially loosen and separate the same from the fiber, and some of these shives will be dropped from the fiber as the fiber passes between the said rollers 18-19. From the last rollers 18-19, the straw or fiber stems will be delivered to the first of a multiplicity of rigidly supported concaves 20 that are connected in a continuous series.

10 Journaled to the frame section 10a and driven in the direction of the arrows marked thereon in Fig. 3a are toothed scutching drums or cylinders 21. Some, or if desired all, of the concaves 20 will be perforated so that the finer shives and seeds will be dropped therethrough. At the junction of the concaves 20, there are rigidly supported toothed grate sections 22, the teeth of which cooperate with the teeth of the drums 21, produce a scutching or whipping action and further removes the broken sheaves from the fiber.

The drums 21 are shown as covered by hoods 23. The said drums driven in the direction of Figs. 3a, to wit; in a counter-clockwise direction, 25 will tend to carry upward some of the seeds, sheaves and fiber; and to prevent this, fans or blowers are applied at the junction of the hoods 23 and arranged to produce a downward blast that prevents the said carrying out action and 30 forces the light materials from the one drum to the next following drum. These fans or blowers involve casings 24 that are open at 25 for the discharge of the downward blast of the fans.

35 Working in each fan casing 24 is a blade equipped fan head 26 that will be driven in a counter-clockwise direction in respect to Fig. 3a by any suitable means.

The drums or cylinders 21 are carried by shafts 27 journaled in suitable bearings on the frame 40 10a. These shafts and their drums may be driven in the direction indicated by any suitable power actuated connections. The last concave 20 leads to a discharge spout or trough 28 that delivers to a tooth picker drum or roller 29 that works over a concave 30. Concave 30 is fixed to the frame section 10b, and the picker drum 28 is carried by a shaft 31 journaled in suitable bearings on the frame section 10b and driven in a counter-clockwise direction in respect to Fig. 3b.

45 50 The rollers 32 and 33 are corrugated and are driven in the direction as indicated by arrows marked thereon in Fig. 3b so that the fiber stock will be advanced between the upper and lower rollers. Preferably the upper rollers 33 will be 55 downwardly spring pressed by same means as referred to in respect to the upper rollers.

The corrugations of these rollers 32 and 33 will preferably be about the same as last rollers 18 and 19 or as illustrated will each have about 60 approximately fifty-six corrugations so that they will soften up and render finer all the sheaves still adhering to the fiber. The last rollers 32 and 33 deliver to fixed concave 34 over which works a toothed picker drum 35 carried by shaft 36 journaled in suitable bearings on the frame 10b. Shaft 36 and drum 35 will be rotated in the direction of the arrow shown in Fig. 3b, to wit; in a counter-clockwise direction.

65 70 By the rotation of drum 35 the fiber will be combed or straightened and delivered to a vibrating shaker rack 37, carried by a rock shaft 38 mounted in suitable bearings on the frame 10b and arranged to be vibrated vertically. The vertical vibration of rack or shaker 37 may be produced in various ways, but, as shown, shaft 38 is

provided with an upstanding arm 39 which, by connecting rod 40, is connected to a power driven rotary crank 41 (see Figs. 2b and 3b). By the shaking action of the rack 37 the remaining loosened shive will now drop from the fiber.

To insure delivery of the fiber from concave 34 and picker drum 35, another fan is provided. This fan includes a casing 42 and a power driven rotary fan head 43. Fan casing 42 has a downwardly opening air discharge port 44.

By a suitable endless conveyer 45 the fiber will then be delivered to a set of power driven lower corrugated finishing rollers 46 and upper corrugated rollers 47, which rollers deliver in the direction marked by arrows in Fig. 3b.

10 15 20 25 30 35 The last of rollers 46-47 deliver the fiber to a breaker drum or cylinder 48 carried by a shaft 49 journaled in suitable bearings on the frame 10b. This drum 48 is driven in the direction of the arrow marked thereon in Fig. 3b, to wit; in a clockwise direction and cooperated therewith with rollers 50 journaled in the crown-like extension of the frame 10b and arranged to press the fiber against the surface of said drum 48. The surfaces of the drum 48 and rollers 50 are preferably so finely corrugated that the corrugations do not well appear on the drawings. However, in some cases the surfaces of said drum and rollers may be substantially smooth or slightly roughened by sanding. The said elements 48 and 50 operate on the stock to press the fiber and loosen therefrom any fine fragments of shive or wood particles that may adhere thereto.

35 40 45 50 55 From the drum 48 the fiber is delivered to a fixed concave 51 over which works a picker drum 52 carried by a power driven shaft 53 journaled in suitable bearings on the frame 10b. This picker drum and its shaft are driven in the direction of the arrow marked thereon, to wit; in a counter-clockwise direction and at such speed that the fiber will be discharged through a spout 54 and preferably delivered to a baling machine indicated as an entirely by the character 55.

Insofar as this invention is concerned, the various rotary parts of the machine may be driven by any suitable means. In fact, the various drums and rollers might be individually driven by electric motors or the like or by various gear and belt drives. In the drawings, the conventional gear and belt drives are suggestively indicated, but as these drives constitute per se no part of the present invention, the elements thereof are not specifically described or marked with the identifying characters. The only thing important about the driving mechanism is that the several rotary drums and rollers and the like be driven in the direction of the arrows marked on the drawings.

Summary of operation

60 65 70 75 80 The fiber as it comes from the field or in similar condition will, by the means already described, be delivered on to the rack-like spreader belt 15 and by the latter will be spread out in an even sheet and delivered to the first breaking rollers 18-19. Moreover, the conveyer belt 15 will be subjected to more or less vibrating which will cause the seeds, if any, to be shaken through and dropped from the fiber. By the progressive action of the corrugated rollers 18-19, which as already described have corrugations of progressively increasing fineness, the woods portion or shives will be broken progressively into shorter and shorter lengths. Some of the shives will be dropped from between the said breaking rollers.

The fiber thus initially treated will be delivered to the first scutching drum or cylinder 21 and by the latter will be carried over the upper surface concave 20 and will thereby be subjected to a scutching or carding action which tends to straighten out the fiber and to remove the shives therefrom. The stripping action is accelerated as the fiber is, by the successive scutching drums or cylinders 21, carried past the several tooth grates 22. These actions are repeated over and over again as the fiber is treated by the several scutching drums and concaves. Some of the concaves, and especially those near the delivery part of the series will be perforated for the discharge of seed and more or less of the loosened shives.

The manner in which the material is blown downward by the fans or blowers 24-26 as the fiber is delivered from the one scutching drum to the other has already been described and, of course, is highly important in that it insures against carrying upward and over of the fiber by the said drums rotated in the counter-clockwise direction in respect to Fig. 3a. The casings 24 of the fans or blowers have the customary axial intake ports for the free supply of air, such as usually provided in fans of the character illustrated.

From the last scutching drum or cylinder 21 the fiber will be delivered to the tooth picking drum 29 and by the latter will be further scutched and scraped and then delivered between the first corrugated softening rollers 32-33 and by these rollers the shives or woody portion of the fiber will be further reduced and loosened from the fiber causing dropping of further portions of the shives.

From the last rollers 32-33 the fiber is delivered to tooth picking drum or cylinder 35 and by the latter will be carried against the concave 34. By the toothed drum 35 further shives will be scraped from the fiber and the fiber will be delivered to the vibrating rack or shaker 37. By the air blast from fan 42-43 the fiber will be delivered from the concave 34 on to the shaker 37. The air blast from fan or blower 42-43 blows the fiber downward on to the said shaker and blows the fiber on to the conveyer 45 while the loosened shives will, by the vibration of the shaker, be dropped from the shaker. By the conveyer 45 the fiber, then very well cleared of the shives or woody portions, will be subjected to the finishing rollers 46-47 and by the last of said rollers 46-47 will be delivered to the breaking drum 48 and by the latter will be carried under the pressing rollers 50. The pressing rollers 50 are preferably frictionally driven by the rotation of the drum 48 and by this action the roller is flattened down and straightened out. From the drum 48 the fiber is delivered to concave 51 and subject to tooth picker drum 52 which delivers the fan from the machine, or, preferably and as illustrated, to baling machines 55, which latter may be of any suitable or conventional construction.

What is claimed is:

1. In a machine of the kind described, the combination with a plurality of toothed drums and cooperating concaves, of a fan located above said toothed drums and positioned to discharge a blast of air downwardly between the adjacent tooth surfaces of said drums, a plurality of corrugated breaking rollers operative on the fiber and delivering the same to the first of said concaves,

the second set of corrugated breaking rollers operative on the fiber delivered from said concaves and cooperating tooth drums, and a cooperating tooth drum and concave receiving from said second series of breaking rollers.

2. The structure defined in claim 1 in further combination with a vibratory shaker receiving from the last noted tooth drum and concave.

3. The structure defined in claim 1 in further combination with a vibratory shaker receiving from the last noted tooth drum and concave, a fan positioned to deliver a blast of air on to the fiber delivered to said shaker from said last noted toothed drum.

4. The structure defined in claim 1 in further combination with a vibratory shaker receiving from the last noted tooth drum and concave, a fan positioned to deliver a blast of air on to the fiber delivered to said shaker from said last noted toothed drum, a third series of breaking rollers 20 operating on the fiber delivered from said shaker, and a breaking drum and cooperating presser roller operative on the fiber delivered from said third series of breaking rollers.

5. The structure defined in claim 1 in further combination with a vibratory shaker receiving from the last noted tooth drum and concave, a fan positioned to deliver a blast of air on to the fiber delivered to said shaker from said last noted toothed drum, a third series of breaking rollers 30 operating on the fiber delivered from said shaker, and a breaking drum and cooperating presser roller operative on the fiber delivered from said third series of breaking rollers, and a tooth picking drum and cooperating concave operating on 35 the fiber delivered from said last noted drum.

6. In a machine of the kind described, the combination with a plurality of toothed drums and cooperating concaves and breaking rollers delivered thereto, of an endless open mesh spreading conveyer operative to deliver the fiber to said breaking rollers, a plurality of toothed drums and cooperating concaves operative on the stock delivered from said breaking rollers, a second set 40 of breaking rollers operative on the fiber delivered from the last of said toothed drums, a toothed drum and cooperating concave operative on the fiber delivered from said second set of breaking rollers, a shaker operative on the stock delivered 45 from said last noted drum and concave, a third set of breaking rollers operative on the stock delivered from said shaker.

7. In a machine of the kind described, the combination with a plurality of toothed drums and cooperating concaves and breaking rollers delivered thereto, of an endless open mesh spreading conveyer operative to deliver the fiber to said breaking rollers, a plurality of toothed drums and cooperating concaves operative on the stock delivered from said breaking rollers, a second set of 50 breaking rollers operative on the fiber delivered from the last of said toothed drums, a toothed drum and cooperating concave operative on the fiber delivered from said second set of breaking 55 rollers, a shaker operative on the stock delivered from said last noted drum and concave, a third set of breaking rollers operative on the stock delivered from said shaker, and a breaking drum 60 and cooperating presser rollers operative on the fiber delivered from said third set of rollers.

8. In a machine of the kind described, the combination with a plurality of toothed drums and cooperating concaves and breaking rollers delivered thereto, of an endless open mesh spreading 65

conveyer operative to deliver the fiber to said breaking rollers, a plurality of toothed drums and cooperating concaves operative on the stock delivered from said breaking rollers, a second set 5 of breaking rollers operative on the fiber delivered from the last of said toothed drums, a toothed drum and cooperating concave operative on the fiber delivered from said second set of breaking rollers, a shaker operative on the stock delivered from said last noted drum and concave, a third set of breaking rollers operative on the stock delivered from said shaker, a breaking drum and 10 cooperating presser rollers operative on the fiber delivered from said third set of rollers, a baling machine receiving the stock delivered from said breaking drum last noted, and a tooth picking drum and cooperating concave interposed between 15 said breaking drum last noted and said baling device and assuring the delivery of the fiber to said baling machine.

9. In a machine of the kind described, the combination with a plurality of toothed drums and cooperating concaves and breaking rollers delivering thereto, of an endless open mesh spreading conveyer operative to deliver the fiber to said breaking rollers, a plurality of toothed drums and

cooperating concaves operative on the stock delivered from said breaking rollers, a second set of breaking rollers operative on the fiber delivered from the last of said toothed drums, a toothed drum and cooperating concave operative on the fiber delivered from said second set of breaking rollers, a shaker operative on the stock delivered from said last noted drum and concave, a third set of breaking rollers operative on the stock delivered from said shaker, a breaking drum and 10 cooperating presser rollers operative on the fiber delivered from said third set of rollers, a baling machine receiving the stock delivered from said breaking drum last noted, and a tooth picking drum and cooperating concave interposed between 15 said breaking drum last noted and said baling device and assuring the delivery of the fiber to said baling machine.

LELAND O. WALKER, 20
Administrator of the Estate of Karl Wessel, De-
ceased.
